AIRPLANE

Mitchell Zurawinski, Niagara Falls, N.Y., assignor to
Bell Aircraft Corporation, Wheatfield, N.Y.

Application September 4, 1958, Serial No. 52,392

Term of patent 14 years

(Cl. D71—1)

Fig. 1 is a top plan view of an airplane showing my new design;

Fig. 2 is a side elevational view thereof;

Fig. 3 is a front elevational view thereof; and

Fig. 4 is a fragmentary sectional view, on enlarged scale, taken on line IV—IV of Fig. 3.

The airplane is symmetrical; the opposite side being essentially like the side shown in the drawing.

I claim:

The ornamental design for an airplane, as shown and described.
